Application March 23, 1933, Serial No. 662,235

16 Claims. (Cl. 84—385)

This invention relates to improvements in wood wind musical instruments, and it is described specifically with relation to improvements in saxophones, although the instruments need not necessarily be made of metal.

Wood wind instruments are musical instruments in which the length of a pulsating column of air and the number of segments in which the pulsating column is divided may be altered by opening lateral holes; the control of the lateral holes is effected by key mechanism, and the present invention has the object of improving the arrangement of the key mechanism on instruments of this character.

It is an object of the invention to provide key mechanism which will enable the player of the instrument to cover or uncover respectively tone holes which are either too large or too numerous to be controlled directly by the digits of the hands of the musician, and it is also an object of the invention to provide an instrument in which the key mechanisms are adapted to control these tone hole covers by fingers of the player which are more or less remote from said covers. It is, furthermore, an object of the invention to provide key mechanism of a similar type for controlling the register holes or octave holes which are to be opened when it is desired to sound higher notes by causing the air column to pulsate in an increased number of segments.

It is another object of the invention to improve the key mechanism for the purpose of increasing rapidity and ease of operation by the fingers, assuring at the same time accuracy and noiselessness of the operation.

Another object of the invention is to improve the key mechanism of these instruments by assuring the permanence of the regulation of the keys or permitting respectively the proper operation of the keys even though a slight misuse of certain parts of the instrument should accidentally take place after the proper setting of the keys.

It is also an object of the invention to enhance the convenience of holding the instrument while operating the keys. This increase of the convenience has become important on the ground that in numerous instances, various combinations of keys may be used for obtaining similar notes owing to the necessity of rapid execution of musical passages in various signatures or for the rapid execution of passages containing accidental sharps and flats.

It is, furthermore, an object of the invention to provide an upper octave key on an instrument of this character in association with a removable mouth pipe of the instrument and to guard said upper octave key against injury which otherwise might be produced by the attachment or adjustment of this removable mouth pipe.

For this purpose it is an additional object of the invention to provide an improved octave key mechanism wherein the arm for operating the mouth pipe key moves in a direction contrary to that employed heretofore for the same purpose. 5

Another object of the invention is to provide an octave key mechanism whereby through the actuation of a single thumb-key, the upper or lower octave hole on the instrument is opened, the change from one to the other octave hole 10 being made automatically according to whether the note played is above G-sharp or below A. In connection with this mechanism, it is an object of the invention to provide an automatic structure which will effect the opening or closure 15 of the proper one of the two octave holes with the opening or closing of the tone hole emitting A.

Another object of the invention is to improve the means by which the mouth pipe may remov- 20 ably be secured to the body of the instrument.

It is, furthermore, an object of the invention to provide improved mechanism for maintaining undisturbed operation of the lower octave key by providing means which prevent the binding 25 of the lower octave key which might otherwise be produced by end pressure on the thumb key, this end pressure having been encountered in other instruments making use of octave mechanism of this class and wherein the two keys had 30 been arranged to turn about a common axis. The accidental end pressure on the thumb plate which may be used for operating the lower octave key, is due to the manner in which the instrument frequently is supported when being played. The 35 instrument is frequently maintained firm in its position by a strap hooked to the body of the instrument and passing about the musician's neck. In sliding the left thumb on the thumb plate, it has been found that frequently an end thrust 40 accidentally is exerted upon the thumb plate, but this end thrust which might set up a binding effect on the key also may be exerted occasionally by the flexing of the spring which actuates the 45 key.

Another object of the invention is to arrange in a novel manner four finger-pieces of keys adapted to be played by the little finger of the left hand. Three of these keys control notes which are below the normal range of the instrument and also control the G-sharp in and on the staff. The fourth of these finger plates is associated with the key for controlling the G-sharp key only. 50

Another object of the invention is to provide 55 an improved key mechanism in association with the G-sharp trill key.

It is, furthermore, an object to provide an improved mechanism for the alternate of E-flat on the first line and in the top space. 60

It is, furthermore, an object of the invention to provide a simple, noiseless and durable mechanism for obtaining B-flat by pressing with the two index fingers only.

5 Another object is to provide a guard on the lower part of the left side of the instrument to prevent the clothing of the player from interfering with the action of the mechanism,—a condition which might occur owing to the fact that the instrument frequently is held against the right hip of the player at its lower end.

10 It is, furthermore, an object of the invention to render this guard device readily detachable from the instrument and attachable to the same whenever desired.

15 With these and numerous other objects in view, an embodiment of the invention has been illustrated in the accompanying drawings, to which reference is made in the following specification.

20 In the drawings,

Fig. 1 is a side elevation of a saxophone embodying the improvements of the present invention;

25 Fig. 2 is a front elevation of the key and lever structure for controlling the upper octave hole and other tone holes;

Fig. 3 is a cross-section on line 3—3 of Fig. 2;

Fig. 4 is a longitudinal section and part elevation on line 4—4 of Fig. 2;

30 Figs. 5, 6 and 7 are longitudinal cross-sections and part elevations similar to Fig. 4 of additional forms for supporting a hinge sleeve while preventing the exertion of end thrust against the same;

35 Fig. 8 is a perspective view of a portion of a key guard;

Fig. 9 is a fragmentary detail section and part elevation of the key guard illustrated in Fig. 8;

40 Fig. 10 is an elevation of an assembly of finger plates and keys adapted to be controlled by the little finger of the left hand, and also illustrating the connection with the G-sharp trill key and fragments of the forked E-flat mechanism;

45 Fig. 11 is an end view against the upper edge of the key plate assembly illustrated in Fig. 10 combined with a cross-section of the body on which the structure is mounted;

50 Fig. 12 is an edge view of the key plate assembly illustrated in Fig. 10 viewed from the left of the figure;

Fig. 13 is a bottom plan view of the finger plate for the G-sharp key and a portion of the arm extending therefrom;

55 Fig. 14 is a side elevation of the G-sharp key and a portion of the body on which it is mounted;

Fig. 15 is a bottom plan view of the finger plate of the B-natural key which forms a part of the assembly illustrated in Fig. 10;

60 Fig. 16 is a fragmentary cross-section on line 16—16 of Figs. 10 and 14 respectively;

Fig. 17 is an enlarged elevation of the forked E-flat mechanism shown in Fig. 1;

65 Fig. 18 is a cross-section on line 18—18 of Fig. 17, in combination with the body of the instrument on which this part of the key mechanism is secured;

Fig. 19 is an elevation of a portion of the body showing another association of key mechanisms mounted thereon;

70 Fig. 20 is a cross-section on line 20—20 of Fig. 19 with the pad for the G-tone hole in closed position;

75 Fig. 21 is a cross-sectional view similar to that of Fig. 20 with the pad for the tone hole G in open position;

Fig. 22 is an end elevation of a cross arm secured to the pad of one tone hole and adapted to operate a pad of another tone hole; and

Fig. 23 is partly an end elevation and partly a section of the joint by which the mouth pipe is 5 detachably and adjustably secured to the body of the instrument.

The body of the instrument, as shown in Fig. 1, is composed of the longitudinal branch 1 which preferably tapers in one direction, the bow or 10 bend 2 which continues the taper in the same direction, and the bell or flare 3, these three parts being firmly united as by soldering or the like. A curved mouth pipe 4 is removably secured to the upper end of the branch 1, and this 15 mouth pipe has at its upper extremity the usual tuning device which does not form a part of the present invention, and the mouthpiece 6.

The upper octave key 8 is disposed on the concave side of the mouth pipe 4, and in the 20 present invention, therefore, the upper octave hole socket 9 is located near the upper end of the mouth pipe 4 and on the lower side of said end. The details of this socket are not illustrated, but it may be assumed that for the purpose of avoiding the flow of condensed fluid or of saliva into the upper octave hole, the socket may consist of a short tubular stud, the inner end of which projects slightly above the adjacent circumferential inner wall surface of the 25 mouth pipe.

The upper octave key 8 comprises a bar the curvature of which corresponds approximately to the curvature of the mouth pipe 4, and this bar is pivoted to the heads of the posts 10, Figs. 35 1 and 2, the pivotal support including the cross arms 11 which extend from both sides of the key. While the upper end of this key 8 carries the pad or stopper 12 for the upper octave hole socket and is yieldingly urged to closed position by a spring (not shown), the lower end of the key is provided with a transversely curved segmental plate 13 of relatively great length and approximately equidistant to the body 1, to assure proper 40 operation even if the accurate alinement of the parts should have been disturbed. In order to move the key 8 to open position, a pressure is exerted upon this abutment or segmental plate 13. The pressure is applied through a companion abutment 14 formed as the upper end of a 45 bar 15, which is provided with a cork inlay, not illustrated, to avoid the production of disturbing clicks or noises.

The bar 15 carrying the companion abutment 14 is not directly secured to the body of the instrument, but is carried in such manner as to be properly actuated in different ways. For this purpose the abutment bar 15 carries fixedly two spaced parallel links 16, 17 which are both pivotally secured to a bar 18 extending parallel to the abutment bar 15. To this bar 18 two links 19, 20 are fixedly secured, and their opposite ends are fixed to a hinge sleeve 21 which is rotatable on a rod 22, Fig. 4, supported in posts 23 and 24. This hinge sleeve is firmly connected with a 65 thumb-piece 25. A spring, not illustrated, has a tendency to maintain this depressible thumb-piece spaced from the body of the instrument, while upon depression of the thumb-piece, the sleeve 21 will be rocked and a downward rocking movement will be transmitted by the parallel links 19, 20 to the floating lever structure comprising the bar 18, links 16, 17 and abutment bar 15. The latter will thereby operate the key 8 to 70 open the upper octave hole.

5 A ball-shaped element 26 is secured to the body of the instrument adjacent the abutment end of the bar 15 to limit the upward movement of this end of bar 8; on the upper side, the abutment bar 15 also is provided with a cork inlay 27 or with some other inlay to absorb the clicking noise which might be produced.

10 From the above it will be seen that the operative engagement between the relatively narrow abutment end 14 of the bar 15 and the lower end 15 of the key 8 will be maintained, even though the mouth pipe 4 should be slightly twisted about the axis of the branch 1 of the instrument. It is for this purpose that the contact portion of 15 the key is constructed in the form of a transverse segment of relatively great length.

The link 17 which connects the abutment bar 15 with the parallel bar 18 is extended beyond its point of pivotal attachment with said parallel bar, Fig. 2 and Fig. 3. This extension of the upper link 17 is bifurcated at 28 and receives loosely between the prongs, a slidable block 29. A screw pin 31 is rotatably mounted in this block 29 and the projecting end of this pin is fixedly inserted in the free end of an arm 32 which is pivoted on a short hinge sleeve 33 also surrounding the rod 22, Fig. 4, the latter being extended beyond the post 24 and having its end supported in another post 34. This arm 32 is continued beyond the sleeve 33, and carries at the free end an abutment 35 at the upper face of the stopper 36 which normally is in contact with the lower octave hole socket 37, Fig. 3. This lower octave hole socket is positioned in the body 35 of the instrument below the mouth pipe 4. Upon depression of this stopper 36, as for instance by a pressure exerted upon the abutment 35, the lever 32 is rocked and transmits this movement through the slide block 29 to the link 17, whereby 40 a rocking movement is imparted to the abutment bar 15 of the composite lever structure.

45 It will be seen, therefore, that upon depression of the thumb-piece 25, the parallel bar 18 is rocked downward, and that thereby the abutment bar 15 also is rocked downwardly to open the normally closed upper octave hole.

The G-key 38, shown diagrammatically in Fig. 2, is soldered to the hinge 39 which is pivotally supported on the body by the posts 40, 50 40, and has soldered to it an arm to which the stopper 41 for the A-natural tone-hole is soldered, and it also carries an arm 42 which has the abutment 43 adapted to actuate the abutment 35. The conventional spring, not shown, is fixed 55 in one of the posts 40, and reacts against a suitable abutment on the under side of the hinge 39 in such a direction as to urge the A-natural stopper 41 into the open position and the abutment 43 into contact with the abutment 35 on 60 the lower octave key 32, thereby closing the hole 37.

65 The acts of pressing and releasing the G-key 38 to close or open the A-natural tone-hole, automatically change the opening of the octave holes from the upper one to the lower, or from the lower one to the upper respectively, provided the thumb-key 25 is pressed at the time, thus opening the upper octave hole only for notes above G, and opening the lower octave hole only for notes below A-natural. For this it is only 70 necessary that the spring actuating the hinge 39 be stiff enough so that, acting through the abutments 43, 35, the sliding block 29 and slotted arm 28, 17 and the abutments 14, 13, the relatively weak spring of the upper octave key 8 is 75 overcome. Vice versa, when the G-key 38 is

pressed, the abutment 43 releases the abutment 35 and the relatively weak spring of the upper octave key reverses the mechanism and raises the stopper 36.

The arm 32 is soldered to the short hinge 33 which is pivotally connected to the body so as to turn freely under the influences only of the forces applied to the pin 31 and abutment 35. It is important that this key 32 be free from any binding end-thrust, such as may be applied to the thumb-key 25. The preferred construction for accomplishing this is shown in Fig. 4, in which the ends of the hinge 33 fit freely between the faces of the posts 24, 34 which support the steel rod 22 on which the hinge 33 fits. 15

An alternative construction for protecting the lower octave key 22 against end-thrust is shown in Fig. 5. In this figure the post 24 (shown in Fig. 4) is omitted, and the thumb-key hinge 21' is continuous between the faces of the posts 23' 20 and 34', by which it is pivotally supported either by pivot-screws (as shown in Fig. 5) or on a steel rod as shown in Fig. 4. The upper end of the hinge 21' is cylindrical at 44, fits inside of the lower octave-key hinge 33, and is provided 25 with a shoulder 27', which keeps the lower octave key 32 in place. Any upward end-thrust which may be imposed on the thumb-key is transmitted to the face of the post 34' and the hinge 33 of the lower octave key is cut slightly shorter 30 than the cylindrical portion 44 of the thumb-key hinge to avoid binding.

Another alternate construction for protecting the lower octave key against end-thrust is shown in Fig. 6. This differs from the preferred construction in having the post 24 replaced by a collar 45, which is secured on the rod 22 by a set screw, and thus prevents the transmission of thrust to the lower octave key 32. 35

Another alternate construction for protecting the lower octave key against end-thrust is shown in Fig. 7, in which the thumb-key hinge is in two parts, 46 and 47, to which are soldered the links 48, 49, the lower one of which has also the crowned shape shown (at 48) in Fig. 3. To the outer ends 45 of these links is soldered the bridge-rod 50, thus transmitting any upward end-thrust to the face of the post 34. The lower octave key hinge 33' fits freely between the opposing ends of the hinged parts 46 and 47. 50

The novel assembly of keys or finger pieces for controlling the G-sharp key and other keys is illustrated in Figs. 10 to 16. This assembly comprises a plurality of flat finger-pieces arranged closely to each other and permitting the little 55 finger to slide from one to the other of these plates, and it also permits the opening of the G-sharp pad by any one of several of these keys, even though the G-sharp finger-piece itself should not be actuated. 60

At a suitable point within the reach of the small finger of the left hand of the player, the G-sharp finger-piece 60 is connected with an arm 61 which is pivotally supported adjacent its lower end, Fig. 14, on a bar 62 extending transversely of the 65 axis of the instrument. A spring 63 normally maintains this arm in a position in which the finger-piece 60 is raised. This arm also is deflected laterally at 64 near the finger-piece 60 which has substantially triangular shape, with the elongated base of the triangle transversely of the axis of the instrument. 70

This key controls the pad 65 for the G-sharp tone hole, and this pad or stopper is mounted on an arm 65' extending from a sleeve 66 under 75

control of a weak spring—not shown—which tends to hold the pad 65 in open position. The arm 61 is provided with a notch 67 into which another arm 66, extending from the sleeve 68, normally lies, this arm being adapted to rock the sleeve and thereby open the pad 65 when the finger piece 60 is depressed. A small piece of cork 69 cemented to the lower face of the arm 61 prevents the disagreeable click, or other noise, which would be caused by engagement of the arm 61 with the body of the instrument. It will be seen, therefore, that upon depression of this last named arm the normally closed pad 65, under action of its spring will be raised.

15 The assembly of finger-pieces associated with the G-sharp finger piece 60 comprises a low C-sharp finger piece 70, a low B finger-piece 71, and a low B-flat finger piece 72, these finger-pieces being arranged to form a substantially rectangular plate assembly wherein the several finger-pieces, however, are operable independently of each other.

15 The low C-sharp finger-piece 70 has an arm which is fastened to a long hinge 73 extending parallel to the axis of the instrument and supported in suitable posts. At the opposite end of this hinge 73, a curved arm 74 is secured, which carries the low C-sharp stopper 75 having its inner face directed upward, as shown, so that upon a depression of the finger-piece 70, the pad 75 is moved to open position, while upon release of the finger-piece 70, this pad is held closed by means of a spring, not shown. The finger-piece 70 is provided on its under face with a short angle piece 76, Fig. 11, the horizontal arm of which normally rests on the deflected portion 64 of the arm 61 for the G-sharp key 60. It is obvious, therefore, that upon depression of the low C-sharp finger-piece 70, this angle piece or wiper 76 will have the effect of also depressing the upper end of the arm 61 in the same manner as if the finger-piece 60 would have been depressed by the little finger to permit the G-sharp pad 65 to swing to open position, while simultaneously therewith, the low C-pad 75 carried at the lower end of the hinge 73 is opened.

50 The plate assembly of finger-pieces also comprises a finger-piece 71 for the low B-key, which in this assembly is surrounded by the other plates 60, 70 and 72, and which is fixedly connected by means of an arm to a hinge sleeve 77 supported by posts and extending parallel to the axis of the instrument. In the embodiment shown, this hinge 77 carries fixed thereto an arm 78 for the low B-pad 79 which is normally open. It is obvious, therefore, that upon depression of the finger-piece 71, this low B-pad 79 will be closed against the action of a spring, not shown, which holds it normally open. This finger-piece 71, however, 55 also is provided on its lower face with an angular extension 80 overlying the deflected portion 64 of the arm 61, for the finger-piece 60, so that upon depression of the low B-key 71 approximately centrally located in the assembly of finger-pieces 65 at the upper end, the G-sharp pad 65 also will be actuated, this pad as described above, being then opened under the action of a spring, not shown, since the arm 66 may follow the downward movement of the arm 61.

70 The fourth finger-piece 72 forming part of the assembly of finger-pieces described, serves for actuating the low B-flat pad 81. The key 72 is equipped with an arm rigidly secured to the hinge 82 which again is supported in posts and 75 extends parallel to the hinges 73 and 77 between

the same. This finger-piece 72 overlies the arm 80 which extends from the low B finger-piece 71, so that upon depression of the low B-flat finger-piece 72, the low B-key 71 also will be depressed, as will be seen from Fig. 12, in which an extension 83 of the wiper 80 is shown directly below the lower surface of the key 72. Upon depression of this key 72, therefore, the low B-natural pad 79 is being depressed, and at the same time the pad or stopper 65 for G-sharp is actuated by being released from closing position, since the angle piece 80 of the low B-key 71 actuates the G-sharp arm 61.

15 The assembly of finger-pieces or plate structure indicated at the upper end of Fig. 10, has a 15 number of great advantages over the conventional arrangement of the finger-pieces for the same pads on other instruments. The arm 61 of G-sharp key 60 being pivotal about an axis transverse to the axis of the instrument, renders 20 the finger-piece 60 adapted to move in a direction which is natural for the little finger of the left hand (which actuates this finger-piece). Another advantage of this structure is that slip between this finger-piece 60 and the wiper 76 25 on the low C-sharp key 70 as well as slip between said finger-piece and the wiper 80 of the low B-key 71 is eliminated, these wipers also being adapted to operate the G-sharp key. This arrangement, furthermore, makes it possible that 30 the low B-flat key 72 likewise operates the G-sharp key 60 owing to its action on the extension 83 on the low B-key 71.

35 The arm 61 extending from the G-sharp finger plate 60 and pivotally supported on a transverse axis 62 is provided at its lower end with an angular extension 84, which as illustrated in Figs. 10 and 16, overlies a cam 85 fixed to the hinge sleeve 86, to which the arm 87 for a G-sharp trill key 88 is secured. The extension 84 of the 40 arm 61 of the G-sharp finger plate 60 is normally held in cam engaging position, as indicated, Fig. 16, owing to spring 63, Fig. 14. Upon a pressure being applied to the finger plate 60, or upon a pressure being exerted from above on the deflected portion 64 of the arm 61 by the wipers 76 45 or 80 respectively, the extension 84 will move away from the cam 85 which is fixedly associated with the hinge sleeve 86 of the G-sharp trill key 88. This hinge sleeve 86 is freely rotatable 50 on its steel rod which is supported in posts in the usual way on instruments of this character, and the G-sharp stopper thereby will be adapted to drop into engagement with the corresponding tone hole, not shown, on the body of the instrument. A trill to G-sharp tone, therefore will be produced upon opening the G-sharp pad 65 55 which is normally in closed position.

60 The offset portion 64 of the arm 61 for the G-sharp plate 60, is, as indicated in Fig. 11, approximately at the level of the axis of the hinge sleeves 77 and 82 which are associated with the keys 71 and 72 respectively, thereby avoiding or minimizing the slip of the wiping surfaces. This offset portion 64 also has such angular relation 65 to the arm 61 to produce the correct lever arm ratios for insuring that the contacts are without backlash at the extremes of the motion imparted to the arm either by actuation of the G-sharp key 60 independently of any of the other keys, 70 or by the actuation of any of the other keys 70, 71 and 72 respectively, each of which will upon depression also cause a depressing movement of the arm 61.

75 In order to facilitate the proper operation of 75

the keys 60, 70, 71, 72 in the plate structure assembly illustrated at the top of Fig. 10, adjacent keys are equipped with rollers positioned at the marginal portions of these keys. The low C-sharp key 70 and the low B-flat key 72, for instance, are provided with the rollers 89 and 90 respectively at adjacent edges to facilitate the sliding motion of the tip of the little finger from one key to the other.

10 The roller 90 on the low B-flat key 72 is more important, owing to the fact that the end of the finger would have a tendency to catch at the edge of the plate 72 when sliding from the depressed key 70 to the undepressed key 72 which is to be 15 operated next. In prior instruments, rollers for these keys were located parallel to the axis of the little finger which had to impart the depressing movement to the keys. The little finger normally is too weak to produce this depression of key 20 72 by a lateral movement parallel to the axis of the instrument, and heretofore these rollers were disposed, as for instance, the rollers 90 and 91 for the low B-key 71, and the low C-sharp key 70 respectively, or the rollers 93, 94 for the low B-key 25 71 and the low B-flat key 72 respectively.

The spring for opening the normally closed pad 65 for the G-sharp key is a very light spring permitting the arm 65' by means of which this pad is secured to the sleeve 68, to turn freely. This spring would have a tendency to open the pad 65 unless it would be prevented by contact of an element which overlies the pad 65. This element is illustrated in Fig. 19 as a bar 95, which extends from a G-natural pad 96 in direction of the axis 35 of the instrument to the G-sharp pad 65. The spring acting on the hinge sleeve 68 for the G-sharp stopper 65 is so much lighter than the spring 63 underlying the arm 61, Fig. 14, of the G-sharp key, that unless the G-sharp key is depressed by any of the means described, the reaction of the strong spring 63 against the body of the instrument will overcome the light spring, not shown, which acts on the pad 65, and will keep said pad in closed condition. The element 40 for returning and holding the pad 65 in this closed position is the bar 95 soldered or secured in some other suitable way to the pad 96 for G-natural.

This pad 96 is secured by means of an arm to a hinge sleeve 97, Fig. 19, which is relatively short, but from which an arm 98 extends outward to carry a link bar 99 having another arm connected to a short hinge sleeve 100 in alignment with the first hinge sleeve 97. This pair of sleeves 97, 100 is adapted to turn freely on a rod 55 which also carries hinges for other pads, as for instance, the hinge sleeve 101, the arm 102 of which is connected with the pad 103 for the F tone-hole. The pad 104 is located directly above the same and serves for controlling the F-sharp hole, while, according to Fig. 1, another pad 105 60 farther down serves for controlling the low and middle E-hole.

The three pads 104, 103, and 105 are in alignment along a line parallel to the axis of the instrument, and they are all fixed to separate hinges turning independently on the same rod 106, Fig. 20. They are, furthermore, actuated by the usual arms or clutches, as shown, and owing to the 65 instrumentalities illustrated in Fig. 19, a depression of any of these pads, 104, 103, or 105 will also induce a depression of the G-stopper or pad 96, with the result that the bar 95 soldered to the pad 96 will then also depress the pad 65 for the 70 G-sharp tone hole.

Two instrumentalities for effecting rotation of the hinge 97 upon depression of the pad 104 or upon depression of the pad 103 are indicated in Fig. 19; the pad 104 for the F-sharp tone hole having an extension on the arm 107, which extension engages from below the connecting bar 99 for the divided hinge 97, 100, so that upon depression of this pad 104, the pad 96 also must be depressed.

Similarly, an arm 108 secured to the hinge 101 10 of the pad 103 for the low and middle F-hole will cause the connecting bar 99 to be actuated for also depressing the stopper or pad 96 for the G-hole, and for closing thereby positively through engagement with the bar 95 the G-sharp tone 15 hole.

This bar 95 extending from the G-stopper 96 to the G-sharp stopper 65 also crosses an arm or wiper 109 which is secured to a hinge sleeve 110, Fig. 19. This hinge sleeve extends upward, and 20 being supported in the usual posts, carries adjacent its upper end by means of the arm 111, a pad 112 for the upper and middle B-hole. This stopper 112 has fixed to it the auxiliary B-flat key 113 which may be played by the first finger 25 of the left hand and may be considered to be fixed on the hinge 110. The key 113 being soldered to the pad 112 for the upper and middle B-hole may, therefore, independently operate this pad. On the other hand, a depression of the stopper 96 30 also may induce a depression of the pad 112 owing to the engagement of the bar 95 with the wiper arm 109 which is secured to the hinge sleeve 110.

The operative surface or front end of the wiper arm 109 has a novel formation inasmuch as this 35 operative surface is curved transversely as well as longitudinally of the axis of the instrument, and may be described as having a spherical curvature. This is fully apparent from Figs. 20 to 22, where this spherical surface is indicated. It 40 will be seen that the radius of this curvature is a relatively short one. By reference to Fig. 22, it will also be noted that this auxiliary element 95 for controlling the closure of the G-sharp pad 65 is provided on its lower surface with a thin 45 cushion 114 of cork, felt, or other sound deadening material cemented thereto and adapted to effect a noiseless operation of the wiper arm 109 and of the G-sharp stopper 65. This noise absorbing cushion 114 extends along the bottom surface of 50 the bar 95 close to the flange of the G-hole stopper 96, and makes the necessary contact for playing the upper and middle B-flat, which is emitted by the tone-hole 115 when all tone-holes between the latter and the mouth-piece are closed.

The spherical curvature of the operative surface of the wiper arm 109 prevents this arm from striking at any time the edge of the cushion 114. Wherever in prior instruments of this character the sharp contact of the wiper arm with the edge 55 of the noise absorbing cushion had not been prevented, this contact against the edge portion had a tendency to loosen the noise absorbing cushion from the arm, producing thereby a metal to metal contact between the arm 95 and the 60 wiper arm 109, thereby spoiling the proper tone control and inducing a clicking noise.

According to Fig. 22, the wiper arm 109 is curved transversely and different relations are indicated in this figure. In the position shown 70 in full lines, the relation of the parts corresponds to that which is shown in Fig. 20, wherein the pad 96, and hence also the pad 65 are depressed. In Fig. 21, the wiper arm 109 occupies an inclined position relatively to the horizontal, and 75

Fig. 22 indicates in dotted lines this angular relation of the wiper arm with respect to the horizontal.

The displacement of the wiper arm 109 may, however, be lengthwise of the bar 95. A displacement of this character may be due to an angular setting between the hinges 97 for the pad 96 and the hinge 110 of the wiper arm 109 instead of a parallel setting. If these two hinge axes are not exactly parallel, this angular longitudinal displacement of the arm 109 along the lower surface of the element 95 must necessarily occur. The broken lines in Fig. 22 show the correct relative position of the arm 109 due to the customary springs when the keys are not depressed by the fingers, and this constant pressure results in a dent being made in the sound deadening material 114 of the bar 95, out of which depression the operative surface of the wiper bar 109 would have to move when the keys are depressed. Owing to the transverse curvature of this operative surface,—a curvature of about the radius indicated in Figs. 20 and 21,—a very smooth action is produced.

In Figs. 1, 17 and 18, the stopper for the tone hole for playing forked E-flat is indicated at 115. It is secured by arm 116 to a hinge 117, which is coaxial with the hinge 77 of the low B-key 71. This last named hinge assembly is extended beyond the point indicated in Fig. 10 downward, and another post is provided at the lower end of the rod. A spring, not shown, serves in a known way for normally maintaining the stopper or pad 115 in open position.

The tone hole socket is indicated in Fig. 18 at 118, and this set of elements can be played to emit the low and middle E-flat when the pad is in open condition, while all other tone hole stoppers down to and including the stopper 105 for the E-hole are closed, and all stoppers below this point are not actuated by the fingers of the musician.

The playing of this forked E-flat in the conventional instruments was very difficult, since in the operation of the mechanisms for producing this tone, parallelism of the various hinges was essential.

The irregularity of the axial alignment or parallelism of the various hinges occurred due to the influence of the condense water which may collect in a saxophone. When an instrument of this character is laid down after having been played, the water of condensation runs onto the key pad 118 of stopper 115, Fig. 18, and the excess of moisture on this pad caused it to swell. When the hinge is considerably closer to the tone-hole socket 119 than shown in Fig. 18 (and as it had been previously commonly made), the swelling of any portion of the key pad, and particularly of that portion which is closest to the hinge, prevented it from closing with ordinary pressure at the side farthest from the hinge, and this failure of properly closing the tone hole 119 naturally interfered with the operation of the instrument.

In the present embodiment, the stopper 115 is depressed by applying a force in direction away from the body, this force being applied to an arm 120 which projects from the hinge sleeve 117 towards the left, Fig. 17, and underneath which another arm 121 may engage, the latter being secured to another hinge 122 mounted in axial alignment with the hinge sleeve 86 of the G-sharp trill stopper 88. In the present application the actuating mechanism for the application of the stopper 115 to the forked E-flat hole

relieves the arrangement from crowding together the hinges for the stoppers 96, 104, 103, 105, indicated in Fig. 19. Owing to this arrangement of the various hinges in a very limited space, a satisfactory forked E-flat mechanism had heretofore not been produced. The hinge element 122 may be mounted in the usual posts, such as posts 129 fixed in the instrument body.

Contrasted herewith, the Fig. 18 shows that the operating crank 121 for the stopper 115 is fixed to the hinge sleeve 122, to which is also fixed the key 123 for low and middle E-natural. This key 123 has an extension 124, to the lower surface of which a noise absorbing cushion or pad 125 is secured, Fig. 18. This foot or extension 124 serves as a stop for determining the upward movement of the E-key 123, and since this stop part is located on the outside of the instrument, it is free from derangement by compression or swelling of the sound-deadening pad, which might otherwise be produced if it were on the inside. The posts on which the hinge 122 is located, are so low that the pad 125 moves approximately along a line radial to the body.

The E-key 123 has no spring acting directly on the same. It is maintained in raised condition through the engagement of the wiper arm 120 with the crank 121. It may also be urged towards the raised position by the stopper 103 which it overlies, as shown in Fig. 17, and this stopper 103, therefore, is definitely closed when the player depresses the key 123 for playing the low and middle E.

As shown in Fig. 19, furthermore, the low D-key 130 is carried by a hinge sleeve 131 to which also the stopper 105, Fig. 1, is secured. This key 130 also overlies the stopper 103, as shown in Fig. 19, and when the low D-key 130 is depressed, it will also depress the F-stopper 103, leaving thereby the middle finger of the right hand of the player free to be raised from the E-key 123. Due to this arrangement, the stopper 115 can be lifted, and will open the forked E-flat tone-hole 119 without allowing the F-hole to open.

In order to make the above described forked E-flat mechanism compact and without undue overhanging strains, the post 156 which supports the lower end of the hinge 77 for the low B-key, Fig. 10, is located nearer to the top end of the instrument than is customary. This has the added advantage of making the hinge 77 short, and, in connection with the oblique offset of the stopper-arm 78, results in a more rigid low B-key. The stopper-arm 133 for the low B-flat key 81 is obliquely offset for the same reason, and for effectiveness and simplicity of appearance.

As shown in Fig. 1, the stoppers 81, 79 on the bell of the instrument, and the stopper 115 at the bend are guarded against injury, which otherwise might occur, this injury particularly affecting the stopper arms, and the hinges carrying the arms. These parts also might interfere with the clothing of the player during the operation of the same. The larger instruments normally are held with the lower part against the right hip, and in this manner the arms and stoppers on the left side of the instrument might interfere with the clothing and might become bent or the like.

Guard structures are, therefore, provided and the common guard for these stoppers in the present application is shown in Fig. 1 as comprising a single framework made of a longitudinal fixed bar 140 and a plurality of arms 141, 142, 143 75

extending laterally from said bar on the body of the instrument, the arms 141, 142 bridging the space between the bell and the body and being secured on the bell to another arm 144 which extends substantially in the direction of the axis of the bell. The downward directed ends of these guard elements are secured in posts 145, shown in Figs. 1, 8 and 9. The ends of these arms are provided with circumferential grooves 146, and these grooved ends are inserted in the short posts 145 rising from plates which are soldered or otherwise fixed to the body.

Set screws 147 are then inserted thru these knobs entering the circumferential groove 146 and thereby holding the guard arms in place. Upon removal of the set screws 147, the entire guard structure may, therefore, be readily withdrawn to permit adjustment of the stoppers, the arms, hinges or the like, and may also equally rapidly be restored to position and then again be locked in place by the set screws.

An additional improvement resides in the manner in which the mouth pipe 4 is adjustably connected with the branch 1 of the instrument, the novel adjustable joint for these elements being indicated in Fig. 23. The mouth pipe 4 is provided at its lower end with an enlarged cylindrical sleeve 150 fixedly secured at its upper end at 151 to the lower portion of the mouth pipe, but projecting beyond the lower edge of the mouth pipe. Another sleeve 152 having a sliding fit in the first named sleeve 150 is secured by soldering or in some other way at 153 to the upper end of the branch 1 of the instrument, and the branch and mouth pipe, therefore are adjustable rotatably relatively to each other. A clamping screw 154 extending through the slot 155 maintains the parts in their adjusted position and is arranged to prevent any injury to the upper octave key 8 if the two parts should be turned relatively to each other. In order to prevent the formation of a capillary siphon if the slides are put together wet, the sleeve 150 on the mouth pipe must extend beyond the lower end of the mouth pipe 4 approximately to the distance indicated in Fig. 23. The clamping screw 154 is mounted operatively in a pair of lugs 156 (one only being shown) rigidly mounted on opposite sides of the slot 155, as is well known in the art.

I claim:

1. In a saxophone, a body, a curved mouth pipe in axial continuation of said body, an upper octave key being located on the concave side of said curved mouth pipe, a lower octave key on the body and extending transversely of the upper octave key, means on the body for changing from the upper octave to said lower octave, said means including an abutment bar in continuation of said upper octave key, means for actuating said abutment bar, a floating lever construction operable by the lower octave key, said floating lever construction including a bar parallel to the abutment bar and a link between said last named bars, said link being operable from the lower octave key upon actuation of the G-key while remaining inoperative upon the actuation of the first mentioned means for operating the abutment bar.

2. In a wood wind instrument, the combination of a straight body, a curved mouth pipe in axial continuation thereto, an upper octave hole being located on the concave side of said mouth pipe, an upper octave key extending along the concave side of said mouth pipe, an abutment bar overlying the straight body, a hinge support-

ed from said body, links extending from said hinge to a bar parallel to said abutment bar, additional links extending from said parallel bar to the abutment bar, means for rocking the hinge to actuate the abutment bar and upper octave key, a lower octave hole being located on the straight body, a lower octave key and means extending from the lower octave key to one of said last named links, whereby upon operation of said lower octave key independent of said first named hinge rocking means actuation of the upper octave key is produced.

3. In a wood wind instrument, the combination of a straight body, a curved mouth pipe in axial continuation thereto, an upper octave hole being located on the lower side of said mouth pipe, an upper octave key extending along the under side of said mouth pipe, an abutment bar supported spaced from said body in alignment with the upper octave key, a hinge sleeve supported on the body, a finger piece for rocking the hinge sleeve, a bar parallel to said abutment bar, links extending from said hinge sleeve to said last named bar and being fixedly connected thereto, other links extending from the last named bar to the abutment bar and being pivotally secured to said parallel bar, a lower octave key, a second hinge in alignment with said first named hinge and connected with said lower octave key, said lower octave key being associated with one of said links, means for operating the lower octave key, and means for preventing binding end thrust upon said second named hinge upon actuation of the first named hinge by said finger-piece.

4. In a saxophone, the combination with the saxophone body, of a curved mouthpipe connected with the saxophone body and provided with an upper octave hole, a stopper for said octave hole, said stopper being carried by a tiltable key bar which is arranged wholly on the under side of said mouthpipe and curved to conform to the contour of the latter, and means in alignment with said key bar for tilting the latter to open said octave hole.

5. In a saxophone, the combination with the saxophone body, of a curved mouthpipe connected with the saxophone body and provided with an octave hole on the under side thereof, a stopper for said octave hole, said stopper being carried by a tiltable key bar which is arranged wholly on the under side of said mouthpipe and curved to conform to the contour of the latter, and swingable means in alignment with said key bar for tilting the latter to open said octave hole.

6. In a saxophone, the combination with a saxophone body, of a curved mouthpipe connected with the saxophone body and provided with an upper octave hole on the under side thereof, a stopper for said octave hole, said stopper being carried by a tiltable key bar which is arranged wholly on the under side of said mouthpipe and curved to conform to the contour of the latter, and a bar for tilting said key bar, said bar being movable toward the saxophone body and positioned substantially in alignment with said key bar.

7. In a saxophone, the combination with the saxophone body, of a curved mouthpipe connected with the saxophone body and provided with an upper octave hole on the under side thereof, a stopper for said octave hole, said stopper being carried by a tiltable key bar which is arranged wholly on the under side of said mouthpipe and curved to conform to the contour of the latter, and swingable means arranged on

the same side of the saxophone body for tilting said key bar.

8. In a saxophone, the combination with the saxophone body, of a curved mouthpipe connected with the saxophone body and provided with an upper octave hole on the under side thereof, a stopper for said octave hole, said stopper being carried by a tiltable key bar which is arranged wholly on the under side of said mouthpipe and curved to conform to the contour of the latter, and means carried by the saxophone body for tilting said key bar to open said octave hole, said means including a complementary arcuate element carried by one of the key bar actuating elements.

9. In a saxophone, the combination with the saxophone body, of a curved mouthpipe detachably connected with the saxophone body and provided with an upper octave hole on the under side thereof, a stopper for said octave hole, said stopper being carried by a tiltable key bar which is arranged wholly on the under side of said mouthpipe and curved to conform to the contour of the latter, and means for tilting said key bar to open said octave hole, said means including an arcuate element to facilitate actuation of said key bar regardless of the tortive position of said mouthpipe.

10. In a saxophone, the combination with the saxophone body, of a curved mouthpipe detachably connected with the saxophone body and provided with an upper octave hole on the under side thereof, a stopper for said octave hole, said stopper being carried by a tiltable key bar which is arranged wholly on the under side of said mouthpipe and curved to conform to the contour of the latter, and means for tilting said key bar to open said octave hole, said means including an arcuate element to facilitate actuation of said key bar regardless of the tortive position of said mouthpipe.

11. In a saxophone, the combination with the saxophone body, of a curved mouthpipe detachably connected with the saxophone body and provided with an upper octave hole on the under side thereof, a stopper for said octave hole, said stopper being carried by a tiltable key bar mounted on the under side of said mouthpipe, the lower end of said key bar being provided with a lateral extension on either side thereof, and means carried by the saxophone body and engaging said key bar lateral extension for tilting the latter to open said octave hole.

12. In a saxophone, the combination of a saxophone body provided with a lower octave hole, a stopper for said octave hole, a curved mouthpipe

connected with said saxophone body and provided with an upper octave hole on the under side thereof, a spring actuated stopper normally closing said upper octave hole, an octave key carried by the saxophone body for lifting said upper octave stopper independently of said lower octave stopper, a G-key, spring actuated means associated with said G-key for normally closing said lower octave hole, and mechanism controlled by said keys, whereby, upon depression of both keys, said upper octave hole is closed and the lower octave hole is opened.

13. In a saxophone, the combination of a saxophone body provided with a lower octave hole, a stopper for said octave hole, a curved mouthpipe connected with said saxophone body and pro-

vided with an upper octave hole on the under side thereof, a spring actuated stopper normally closing said upper octave hole, an octave key carried by the saxophone body for lifting said upper octave stopper independently of said lower octave stopper, a G-key, spring actuated means associated with said G-key for normally closing said lower octave hole, and mechanism controlled by both of said keys, whereby, upon depression of both keys simultaneously, said upper octave hole is closed and the lower octave hole is opened by the upper octave stopper spring control.

14. In a saxophone, the combination of a saxophone body provided with a lower octave hole, a stopper for said octave hole, a curved mouthpipe connected with said saxophone body and provided with an upper octave hole on the under side thereof, a spring actuated stopper normally closing said upper octave hole, an octave key carried by the saxophone body for lifting said upper octave stopper independently of said lower octave stopper, a G-key carried by the saxophone body, spring actuated means associated with said G-key for normally closing said lower octave hole, and mechanism controlled by said keys, whereby, upon depression of both keys, said upper octave hole is closed and the lower octave hole is opened, and whereby, upon release of said G-key, and maintaining depression of said octave key, said upper octave hole is opened and the lower octave hole is closed.

15. In a saxophone, the combination of a saxophone body provided with a lower octave hole, a stopper for said octave hole, a curved mouthpipe connected with said saxophone body and provided with an upper octave hole on the under side thereof, a spring actuated stopper normally closing said upper octave hole, an octave key carried by the saxophone body for lifting said upper octave stopper independently of said lower octave stopper, a G-key carried by the saxophone body, spring actuated means associated with said G-key for normally closing said lower octave hole, and mechanism controlled by said keys and including a floating lever operable by said octave key, whereby, upon depression of both keys, said upper octave hole is closed and the lower octave hole is opened.

16. In a saxophone, the combination of a saxophone body provided with a lower octave hole, a tiltable carrier element provided with a stopper for closing said octave hole, a curved mouthpipe connected with said saxophone body and provided with an upper octave hole on the under side thereof, a spring actuated stopper normally closing said upper octave hole, an octave key carried by the saxophone body for lifting said upper octave stopper independently of said lower octave stopper, a G-key carried by the saxophone body, spring actuated means associated with said G-key for normally closing said lower octave hole, devices operatively connecting said lower octave stopper carrier with said upper octave stopper including mechanism controlled by both keys, whereby, upon depression of both said keys, said upper octave hole is closed and the spring action controlling said upper octave stopper is transmitted through said devices and mechanism to said lower octave stopper carrier, thereby opening said lower octave hole.

ALLEN LOOMIS.
